(57) **CLAIM**

The ornamental design for a toy figure, as shown and described.

DESCRIPTION

FIG. 1 is a front elevational view of an outer portion of our new ornamental design for a toy figure;

FIG. 2 is a back elevational view thereof;

FIG. 3 is a right side elevational view thereof;

FIG. 4 is a left side elevational view thereof;

FIG. 5 is a top plan view thereof;

FIG. 6 is a front upper left isometric view thereof;

FIG. 7 is a front upper right isometric view thereof;

FIG. 8 is a front lower left isometric view thereof; and,

FIG. 9 is a rear lower right isometric view thereof.

The dot-dash boundary lines in the figures show portions of the toy figure that form no part of the claimed design.
